Bethia Hoffman Bentley, Esq.

UNITED STATES PATENT OFFICE.

DAVID T. WILLIAMS, OF PATERSON, NEW JERSEY, ASSIGNOR TO VACUUM ENGINEERING COMPANY, A CORPORATION OF NEW YORK.

PIPE-FITTING.

No. 921,039.

Specification of Letters Patent.

Patented May 11, 1909.

Application filed March 19, 1908. Serial No. 422,107.

To all whom it may concern:

Be it known that I, DAVID T. WILLIAMS, a British subject, and a resident of Paterson, county of Passaic, State of New Jersey, have 5 invented certain new and useful Improvements in Pipe-Fittings, of which the following is a full, clear, and complete disclosure.

My invention relates to pipe fittings, and particularly to that class of pipe fittings in 10 which two pipes or conduits are connected to a single object, such as a valve, cock, or similar device, composed of integral or rigidly-connected parts.

My invention is especially applicable to 15 pipes which pass through a wall or partition of a building or room, and the parts of the device are so arranged that the pipes may be installed and the walls of the building or room completely finished, after which the 20 valve or similar device may be placed in position upon said wall without the necessity of removing any portion of said wall or partition. The device is so arranged that all the parts are accessible and easily adjustable 25 in their correct positions.

My invention is of special utility in connection with vacuum or pneumatic cleaning systems, where both the suction and water-pipes pass through the walls of the rooms at 30 the different floors and are connected to a single valve which controls both said suction and said water supply.

Heretofore, in the construction of buildings and the installation of suction and water 35 pipes for vacuum or pneumatic cleaning systems, it has been necessary to leave a considerable portion of the wall adjacent said pipes unfinished, so that access could be had to the branches which enter the room, in order that the usual or ordinary pipe connections might be screwed in place. This means of placing the valves and their connecting pipes in position, has not only delayed the 40 finishing of the walls of the room, but has 45 made it impossible to make the finish as neat and uniform in appearance as it would be if all done at one time.

The object of my invention, therefore, is to 50 provide a connection for connecting a valve or similar object to two adjacent pipes, in a simple and efficient manner, and also to provide a connection that is finished in appearance and one that may be installed without 55 injury to, or displacement of, any of the parts surrounding the pipes or conduits.

For the sake of illustration, I have shown my improved pipe fittings in connection with a unitary double-acting valve, which controls two passages through the same, in this instance one passage being for the suction 60 and the other for the water supply in connection with the vacuum or pneumatic cleaning system.

For a full and detailed description of one form of my invention which I at present 65 deem preferable, reference may be had to the following specification and the accompanying drawing, in which the figure thereof indicates my improved pipe fittings in elevation, the essential parts thereof being shown 70 in vertical cross section.

Referring to said drawing, the numeral 1 indicates a comparatively large suction pipe, and the numeral 2 a smaller or water-supply pipe. These pipes run vertically through 75 the building, and have branches 3 and 4 at each floor on which the supply from said pipes is to be used. The branches 3 and 4 terminate in screw-threaded ends 5 and 6, the screw thread of said ends being preferably 80 parallel in contra - distinction to the tapering screw-threads of ordinary pipe fittings.

Upon the inner surface of the wall 7 of the room I place a suitable plate 8, which may be 85 of circular or of any other preferred or ornamental outline, and which has a lug 9 projecting from its inner side, so located as to extend within the passage 10 in the wall through which the branches 3 and 4 extend. 90 The lug 9 is for the purpose of supporting and holding in position the plate 8 and the parts carried thereby. The plate 8 is held in firm contact with the surface 7 by means of nuts 11 and 12, which engage screw-threaded ends 95 5 and 6 of the branches 3 and 4, and when screwed firmly upon the plate 8 holds said plate firmly against the wall and the pipes 3 and 4 securely in their relative positions. The plate 8 is provided with a marginal flange 100 13, within which is adapted to be seated the flange 14, carried by the valve 15 or similar device, to which the pipes 3 and 4 are connected. The flange 14 is preferably offset as indicated at 16, so as to provide a recess or 105 recesses, within which the nuts 11 and 12 may be seated.

The double tubular portion 17 of the valve or similar device is provided with cylindrical recesses 18 and 19, within which the screw- 110

threaded ends 5 and 6 may pass, and which are also adapted to contain the gaskets or packing 20 and 21. The flange 14 is provided with suitable holes, through which 5 pass the screws or bolts 22, and it will be seen that when these screws or bolts are turned up, they will draw the said flange and its connected valve or similar device toward the plate 8, and will cause the gaskets 20 and 10 21 to be firmly held in position, so as to prevent leakage between the end of the pipes 3 and 4 and the tubular portion 17 of the said valve or similar device. It is obvious that the gaskets or packings 20 and 21 may be 15 placed at any other preferred or convenient point, but I have found that when they are located as indicated in the drawings, more satisfactory results are obtained.

Having thus described my invention, I do 20 not wish to be understood as being limited to the exact details of form or arrangement of parts set forth, for various changes may be made without departing from the spirit and scope of my invention; but

25 What I claim and desire to protect by Letters Patent of the United States is:

1. In combination with a plurality of tubular conduits, a base through which said conduits pass and adapted to be seated 30 against a wall, means for holding the ends of said conduits in a fixed position relative to said base, a unitary device having passages corresponding to said conduits, and means engaging said base for forcing said device 35 into fluid-tight connection with the ends of said conduits.

2. In combination with a plurality of tu-

bular screw - threaded conduits, a base through which said conduits pass and adapted to be seated against a wall, nuts for holding the ends of said conduits in a fixed position relative to said base, a unitary device having passages corresponding to said conduits, and means engaging said base for forcing said device into fluid-tight connection 40 with the ends of said conduits. 45

3. In combination with a plurality of tubular screw - threaded conduits, a base through which said conduits pass and adapted to be seated against a wall, nuts upon the 50 ends of said screw-threaded conduits and engaging said base, a unitary device having passages corresponding to said conduits and also having a flange extending parallel with the said base, and means engaging said flange 55 and said base for forcing said device into fluid-tight connection with the ends of said conduits.

4. In combination with a plurality of tubular screw-threaded conduits, a base-plate 60 through which said conduits pass and adapted to be seated against a wall, nuts upon said screw-threaded conduits and engaging said base-plate, a unitary device having passages corresponding to said conduits and having 65 recesses adjacent said passages, into which the ends of said conduits extend, fluid-tight packing in said recesses, and means for forcing said device toward said base-plate.

Signed this 16th day of March 1908.

DAVID T. WILLIAMS.
